(57) **CLAIM**

The ornamental design for a control panel for automobile air-conditioning systems, as shown and described.

DESCRIPTION

FIG. 1 is a perspective view of the control panel for automobile air-conditioning systems;

FIG. 2 is a top plan view;

FIG. 3 is a front elevational view;

FIG. 4 is a right side elevational view;

FIG. 5 is a left side elevational view;

FIG. 6 is a bottom plan view; and,

FIG. 7 is a rear elevational view.

The broken line showing the back of the control panel is for illustrative purposes only and forms no part of the claimed design.
